UNITED STATES PATENT OFFICE.

ARTHUR J. DEWEY AND ALFRED J. CONKEY, OF NEW LONDON, IOWA, ASSIGNEES OF
ONE-THIRD TO FRANK F. ROBERTS, OF NEW LONDON, IOWA.

COMBINATION STEP-LADDER AND IRONING-TABLE.

1,073,799.

Specification of Letters Patent.

Patented Sept. 23, 1913.

Application filed December 27, 1912. Serial No. 738,964.

To all whom it may concern:

Be it known that we, ARTHUR J. DEWEY and ALFRED J. CONKEY, citizens of the United States, residing at New London, in the county of Henry and State of Iowa, have invented certain new and useful Improvements in Combination Step-Ladders and Ironing-Tables; and we do declare the following to be a full, clear, and exact description of the invention, such as will enable others skilled in the art to which it appertains to make and use the same.

This invention relates to improvements in combined step ladders and ironing tables.

One object of the invention is to provide a device of this character which may be readily converted from a step ladder into an ironing table or from an ironing table into a step ladder and which when not in use as either an ironing table or step ladder may be folded up in close compact form.

Another object is to provide a combined step ladder and ironing table which will be simple, strong, durable and inexpensive in construction, efficient and reliable in operation and well adapted to the purposes for which it is designed.

With these and other objects in view, the invention consists of certain novel features of construction, and the combination and arrangement of parts as will be more fully described and claimed.

In the accompanying drawings: Figure 1 is a side view of our improved combination step ladder and ironing table showing the parts arranged to form the latter; Fig. 2 is a similar view showing the parts arranged to form a step ladder; Fig. 3 is a front view of the device with the parts arranged as shown in Fig. 2 of the drawings; Fig. 4 is a bottom plan view of one end of the ironing board which forms the top of the table and the prop of the ladder; Fig. 5 is a detail horizontal section through the step member of the device taken on the line 5—5 of Fig. 3.

Our improved combination step ladder and ironing table comprises a ladder or step member 1 and an ironing board 2 which when the device is arranged as an ironing table forms the top of the latter as shown in Fig. 1, and when the device is arranged

as a step ladder forms the prop thereof as shown in Fig. 2 of the drawing. The ladder or step member of the device is formed in main outer and supplemental inner sections 55 3 and 4 which are pivotally connected and are adapted to be folded together as clearly shown in Figs. 2 and 3 of the drawings to form the ladder or step member of the device. The outer section 3 of the ladder 60 member 1 comprises side bars 5 the ends of which are offset at points near the centers thereof, said ends being offset to a distance corresponding with the width thereof as shown. The side bars 3 converge from their 65 lower toward their upper ends and are connected by a series of cross pieces 6 which form one-half of the steps of the ladder. The cross pieces 6 of the upper portion of the section 3 form the outer portions of the 70 upper steps of the ladder while the cross pieces in the lower portion of the section form the rear sides of the lower steps of the ladder as is clearly indicated in dotted lines in Fig. 2 of the drawings and in full lines 75 in Fig. 3 of the drawings.

The inner section 4 of the ladder member also comprises side bars 7 which, like the side bars 5 of the section 3 are also offset at points near their center or near the pivotal connection thereof with the side bars 5 of the main section 3, said side bars 7, however, being offset in opposite directions from the side bars 5 so that when the sections 3 and 4 are folded together to form the 80 85 ladder the ends of the side bars of one of the sections form continuations of or extend in line with the opposite ends of the side bars of the other section as is clearly indicated in Fig. 2 of the drawings. The side 90 bars 7 are connected by a series of cross bars 8 which when the sections of the ladder member are brought into engagement, co-act with the cross bars 6 of the other ladder section and form with said bars 6 the treads 95 of the ladder.

The side bars 5 and 7 of the ladder sections 3 and 4 are pivotally connected by a pivot rod 9 which extends through said side bars in the center of the widest portions 100 thereof and arranged through said wide portions of the side bars of each side of the

pivot rod 9 are tie bolts or rivets 10 which are provided to prevent the side bars from splitting at this point. Below each of the cross bars 6 and 8 of the ladder sections is arranged a tie rod 11 said rod serving to brace and strengthen the cross bars or steps of the ladder.

The upper ends of the side bars 5 of the main ladder section 3 are pivotally engaged with the ends of a cross bar or ring 12 which is secured to a block 13 to the opposite edge of which is secured the wider end of the ironing board 2 which forms the prop of the ladder and the top of the table. When the device is arranged as a ladder the block 13 forms the upper step or top of the ladder and is of sufficient width for supporting a bucket or other receptacle. When the device is arranged as an ironing table the block 13 forms a spacing member and support for the end of the ironing board to which the block is attached. In the upper ends of the side bars 7 of the section 4 of the ladder member is a cross bar or rung 14 the purpose of which will be hereinafter described.

Pivottally secured near their inner ends to the inner side of the ironing board and prop member 2 of the device are combined rack bars and ladder supporting legs 15 which when the device is arranged as a step ladder are adapted to be spread apart at their lower ends and to engage the floor and form supporting legs for the prop member 2 of the ladder. The outer ends of the arms 15 are preferably shaped to fit flat against the floor when arranged as supporting legs and the outward movement of the said arms when thus arranged is limited by a chain or flexible connection 16 secured at its ends to the bars and midway between its ends to the inner side of the board 2. The bars are further held in position to form supporting legs by a hook 17 which is pivotally connected at one end to the upper end of one of the bars and is adapted to be engaged with an eye 18 in the other bar as shown in Figs. 2 and 3 of the drawing. The step and prop members 1 and 2 of the device when arranged to form a step ladder are limited in their outward movement or prevented from being spread too far by chains or flexible connections 19 the ends of which are connected to the inner edges of the upper portion of the side bars 5 of the ladder section 3 while the other ends thereof are connected to the inner side of the board or prop member 2 as shown.

When the device is arranged as an ironing table the sections 3 and 4 of the ladder or step member of the device are swung open or to the positions shown in Fig. 1 of the drawings and thereby form supporting legs for the ironing table, the top of which is formed by the board 2 as shown.

When the parts are thus arranged the rung 14 in the upper end of the section 4 is engaged with notches 20 a series of which are formed in each of the bars 15, said notched bars thus forming an adjustable connection for the upper end of the section 4 whereby the sections 3 and 4 may be held in position to support the board or top of the table at different elevations and permitting the formation of a high or low table. When the bars 15 are employed as a connection for the upper end of the table supporting section 4 the hook 17 at the inner end of the bars is disengaged from its eye, thereby permitting the inner ends of the bars to be swung together or to a position wherein the rung 14 and upper ends of the side bars 7 of the section 4 may be readily engaged therewith.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as claimed.

Having thus described our invention, what we claim is:

1. In a combination step ladder and ironing table, a step member comprising two sections, a combined prop and ironing board pivotally connected to said step member and adapted to form a prop when the device is arranged as a step ladder and to form an ironing board or table top when the device is arranged as an ironing table, and means connected to the prop and ironing board member and adapted to form rear supporting legs for the device when arranged as a ladder and to form a stop with which one of the ladder sections is engaged when the device is arranged as an ironing table. 100 105 110

2. In a combination step ladder, and ironing table, a step member, a combined prop and ironing board pivotally connected to said step member and adapted to form a prop when the device is arranged as a step ladder and to form the ironing board or table top when the device is arranged as an ironing table, said step member comprising a main outer section, and a supplemental inner section pivotally connected and adapted to be folded together to form the step member and to be opened out and spread apart to form the supporting member for the top of the table, combined rack bars and ladder supporting legs pivotally secured to the free end of the ironing board or table top, means to hold said bars in position to form diverging legs for said ironing board and table top member when the latter is employed as a prop for the ladder, 125 130

and means in the end of one of the sections of said step member to adjustably engage said combined rack bars and supporting legs whereby said step members are held in position to form supports for the table top when the device is arranged as an ironing table.

5 In testimony whereof we have hereunto

set our hands in presence of two subscribing witnesses.
